6 Claims. (Cl. 179—18)

1

This invention relates to telephone and like selective systems using automatic selecting switches. It is particularly applicable to systems using single motion selecting switches, commonly referred to as uniselectors. With switches of this type, set in accordance with a marking applied to contacts in its bank, the contacts or outlets of a group that can be marked may be variable both in number and position. Different methods of obtaining large groups of outlets have been proposed but the maximum number of contacts which may be traversed by a wiper within the period, known in automatic telephone systems as the inter-train pause, is determined by the speed of operation of the selecting switch. This limitation together with that imposed by the practicable size of the switch determines the number of contacts, and therefore the number of outlets, that can be provided at any one switch. In a particular known type of univector the contact arcs contain 50 outlet contacts, this being a suitable number for a switch operating at a speed of traverse of 200 contacts a second, and by a combination of methods it has been possible to provide a group selecting switch with 200 outlets and to arrange that the wipers in their search for a free outlet have not to pass over more than 50 outlet contacts, so that the time available for searching a group is not exceeded. With such an arrangement, four sets of four wipers and contact arcs have been provided, making a total of sixteen wipers and contact arcs, there being four wipers for each speaking wire and for each test wire, and four marking wipers. The contact arcs may be so arranged that there are four groups of fifty outlets, or other grouping may be arranged in which the total number of groups multiplied by the number of outlets in each group does not exceed 200.

The present invention has in view arrangements whereby the number of outlets that can be had from a selecting switch of a given size and operating at a prescribed speed can be increased beyond that hitherto available.

In the present invention a selecting switch is provided with a plurality of wiper sets, each set comprising two line wire wipers and a test or holding wire wiper, a particular one of these sets being adapted to be connected up in accordance with the number of impulses received at the switch for the purpose of outlet group selection. There is also a marking wiper common to the several sets of wipers and adapted to be connected in the test circuit for determining the outlets which are to be tested. The contacts in

2

the several arcs of the selector are grouped correspondingly and the marking of a group in the marking arc ensures test taking place over contacts situated in like positions in the test wire arcs. If some of the sets of outlet arcs contain only one group of outlets while other sets contain more than one group, it must be arranged that the markings for the single group are made in such a manner that no commoning of the groups of contacts in the marking arc takes place except in the case of digital values denoting a sole group in an outlet arc. The outlet wipers are conveniently connected to contacts of an impulse responsive device such as a digit switch which, by its response to a train of impulses, connects up a particular set of wipers. The contacts of the marking arc may be cross-connected so that in response to impulses denoting a digital value, the contacts marked correspond in position to the contacts of the outlets of the group denoted by that value in the outlet arcs. Where a set of outlet arcs includes outlets in more than one group the corresponding wipers would be connected to a like number of contacts in the digit switch and differentiation between the groups would be effected by a like grouping of the contacts in the marking arc and the marking of the several groups over a further arc of the digit switch. Each outlet group may serve for calls denoted by a pair of digital values and a discriminating signal may be passed forward to the succeeding selector for route selection according to the particular digital value that brought about selection of the outlet. In a similar way the selector itself may be selectable by either of two digital values and may be adapted to receive a discriminating signal for the purpose of route selection. This signal may take effect on a relay a contact of which is adapted in its front and back positions to mark one or other group of contacts in the marking arc of the selector, the outlets being arranged so that one outlet arc includes all the outlets of two groups, one group corresponding in position to contacts in the marking arc marked over the relay contact in the other position.

While a digit switch has been referred to, it will be obvious to those skilled in the art that the impulse responsive device may be a relay chain or combination of relays, contacts of which suitably arranged would be connected in the circuits of the line and test wires and of the marking wiper. The impulse responsive device may also be used for transmitting the signal to differentiate between the two values of a digit indica-

tive of a selected outlet. The impulse responsive device may be included in a circuit common to a number of selectors in which case the selection of the appropriate set of selector wipers may be effected by means of relays in the individual selector circuit and operated by and in accordance with the setting of the impulse responsive device.

Arrangements for carrying out the invention will now be described by way of example with reference to the accompanying drawings which show the circuits of an incoming selector in an automatic telephone system.

Fig. 1 of the drawings shows a selector at the incoming end of a junction that is picked up in response to a single value of a digit, and Fig. 2 shows a selector at the incoming end of a junction that is picked up in response to either of two different values of a digit. The circuits of the incoming selector shown in Fig. 1 will first be described after which a brief description of the circuits of the selector shown in Fig. 2 will be given with a more detailed description of those circuits that differ from those shown in Fig. 1. The selector is a motor driven uniselector, the driving mechanism being designated generally by MU. The selector has 16 wipers and arcs of contacts each arc containing 52 contacts of which 50 are connected to outlets. There are five wipers and corresponding arcs associated with each of the two line wires and the test and holding wire, and a single marking wiper and corresponding arc. The selector is adapted to search in a group of outlets in response to a single digit which may be of only one value or it may be of either of two values, the position in the selector arcs of the outlet group to be searched being marked in the marking arc by a digit switch which also connects up the appropriate set of wipers in the line and test wire circuits. The digit switch is an eleven point stepping switch, the switch being of the reverse drive pawl and ratchet type, and the contact arcs in the line and test wire circuits are connected in pairs to the corresponding wipers of the selector. The outlets from the selector may be grouped in five groups of 50 outlets each or ten groups of 25 outlets each or there may be some groups of 50 outlets and some of 25 outlets, or other grouping arrangements totalling 50 outlets in two groups. In the case of groups of 25 outlets each the corresponding contacts in the arc of the marking wiper, designated G in the drawing, are connected to the relevant contacts in the arc of wiper M4 of the digit switch. A similar connection is made for groups of 50 outlets but in this case 25 outlets are connected to the relevant contact in the arc M4 and the remaining outlets are connected to the relevant contact in the arc of wiper M3. Similar considerations apply to other groupings totalling 50 outlets in two groups. If all the groups contain 50 outlets each the contacts in the arc of wiper G may be earthed directly. As each wiper of the selector can only extend a connection over any one of 50 outlets and is connected to a single contact or a pair of contacts of the digit switch, each selector arc must contain contacts of one group of 50 outlets or two complete groups each of a lesser number of outlets totalling 50. An outlet may, however, be taken into use in response to either of two values of a digit and discrimination between its two values may be effected at the succeeding switching stage by means of a signal passed forward when the selector has switched the connection through. The digit switch, besides the

five wipers referred to, has an off-normal wiper M1, a wiper M2 for determining whether a discriminating signal is to be passed forward or not, and a wiper M3 for the operation of the appropriate overflow meter if congestion of an outlet group is encountered. The digit switch magnet is designated DM and is provided with a self-drive contact dm. The relays shown are the impulse receiving relay A, switching control relay B, slow-releasing dialling relay C, high-speed test relay T and holding relay H. The selector has off-normal contacts N1 and N2.

When the junction is taken into use, relay A operates by means of its right-hand winding in a loop over the junction and wiper M2 to earth connected to the normal contact in the associated contact arc. Contact a1 closes an operating circuit for relay B over resistance YB and magnet DM but the magnet will not operate in this circuit. Relay E on operation holds over its contact b1 and at contact b2 extends earth over wiper M1 at normal to the right-hand winding of relay C. Contact b3 prepares an operating circuit for the driving mechanism MU of the selector, contact b4 prepares an operating circuit for relay H, contact b5 closes a point in the selector test circuit, contact b6 maintains earth on the positive junction wire after impulsion has commenced, and contact b7 connects earth to wiper M3, lighting lamp PG over the normal contact in its contact arc and closing a circuit for a delayed alarm relay. Consequent on the operation of relay C, contact c1 connects the low resistance left-hand winding of that relay in the operating circuit for magnet DM which is not closed at this time, contact c2 opens a point in the initial operating circuit of the selector driving mechanism MU, contact c3 opens a point in the operating circuit for relay H, and contact c6 disconnects the arc of contacts of wiper M2 from the positive junction wire. The magnet DM will not operate in series with relay B. The impulses received by relay A are repeated to magnet DM in the following circuit: earth over contact b4, back contact a1, contact c1, left-hand winding of relay C, and contact h7 in parallel with resistance YB, magnet DM to battery. Magnet DM responds to the repeated impulses and steps the digit switch accordingly. At the first step of the digit switch, the circuit of the delayed alarm relay is opened at wiper M3 and lamp PG is extinguished. When relay A releases, contact a1 short-circuits relay B exerting a delaying effect on that relay so that it does not release during the impulse break period. As soon as relay A re-operates after the first impulse break, the digit switch is stepped from its normal position and thereafter relay C remains operated by the operating current of the digit switch magnet during impulse break periods and is held by means of its copper slug during the shorter impulse make periods. At the end of the impulse train, relay A remains steadily operated and after a brief interval relay C releases. The circuit of the selector driving mechanism MU is now closed from earth over wiper M1, contacts b3, c2, t1, and h1. The operating right-hand winding of relay H is short-circuited at this time. The selector is set in motion and as soon as its wipers leave their normal position, the off-normal contacts are operated. Contact N1 maintains the operating earth for the mechanism MU and contacts N2 leave relay B dependent on its contact b1. According to the setting of the digit switch by the received train 75 of impulses, a particular set of wipers of the se-

lector is selected by wipers **M5**, **M6** and **M7**, and the contacts of the marking arc associated with wiper **G** of the selector are marked over wiper **M4** or over wipers **M3** and **M4**. If the outlet group designated is a 25 outlet group, the appropriate contacts in the arc of wiper **G** are earthed over wiper **M4** while if the outlet group contains 50 outlets, 25 of these will be marked over wiper **M3**. If any other grouping is provided, the marking will be arranged in a similar manner to that described for a group of 50 outlets. When the selector wipers reach contacts in the desired group, the test relay **T** is connected on one side over wiper **M7** to the test wiper selected by the digit switch and on the other side over wipers **G** and **M4** or **M3** to earth. When a free outlet is encountered, relay **T** operates in the following circuit: earth over wiper **M4**, or earth over contact **b7** and wiper **M3**, wiper **G**, rectifier **MRA**, both windings of relay **T** in series, contact **b5**, wiper **M7**, the selected test wiper to battery on the test wire of the outlet. Contact **t1** opens the operating circuit for the mechanism **MU** and switches the high resistance right-hand winding of relay **H** in series with the magnet, and in its front position contact **t1** short circuits the lower winding of relay **T** and connects a low resistance earth to the test wiper to busy the outlet. Relay **H** operates in series with mechanism **MU** but the resistance of the circuit is too high for the mechanism to remain operated so that the switch is stopped. Contact **h1** opens a point in the operating circuit for the mechanism **MU**, contacts **h2** and **h3** switch through the line wires and open the circuit of relay **A**, contact **h4** connects both windings of relay **H** in series between battery over mechanism **MU** and earth on the test wiper, contact **h5** maintains earth over contact **c4** on wiper **M3** and prepares for the operation of an over-flow meter if necessary, contact **h6** prepares for the transmission of a busy signal if necessary and contact **h7** opens a point in the self-drive circuit for magnet **DM**. Relay **A** releases. Following on the seizure of the outlet, earth is applied in the succeeding circuit to the test wire thereby short-circuiting relay **T** and bringing about its release, and holding relay **H** independently of relay **B** which commences to release by reason of its being short-circuited over contact **a1** on the release of relay **A**. When relay **B** releases, the homing circuit of the digit switch is prepared at contact **b3** and earth is disconnected from the junction point of the two windings of relay **H** at contact **b4** and the test relay is disconnected at contact **b5**. Contact **b6** disconnects earth from the positive wire if this has been applied as will be referred to later. At the end of the conversation, release is initiated by the disconnection of earth from the test and holding wire and relay **H** is released. Contacts **h2** and **h3** and **h4** disconnect the line and test wire wipers, contact **h1** connects earth over contacts **N1** and **t1** to mechanism **MU** and contact **h1** closes the homing circuit for the digit switch which self-drives by the operation of its magnet over wiper **M1**, contacts **b3**, **dm** and **h7** until the normal position is reached in which the circuit is opened at wiper **M1**. The selector homes by the operation of the mechanism **MU** in the above described circuit until it reaches normal where the circuit is opened at contacts **N1**.

If an outlet is selectable by a pair of values of a digit, a discriminating signal is sent forward following the operation of relay **H**. The values of a pair may be and conveniently are an odd

value and an even value. If the value is odd, then, following the operation of relay **H**, the subsequent impulse-receiving relay will operate round the junction loop in series with a discriminating relay. If the value is even, the positive junction wire will be earthed over contact **b6**, wiper **M2** and contact **c6**, and the said discriminating relay will be shunted and prevented from operating. This earth is subsequently disconnected by the release of relay **B**. The operation or non-operation of the discriminating relay will bring about an operation such as that described in connection with Fig. 2 or a wiper selection or wiper movement for selection in a particular 10 main group. Arrangements of this latter kind are described in British Patent No. 378,585.

If an outlet group is found congested, the selector wipers continue in rotation until the last contacts in the arcs are encountered whereupon the 20 selector is stopped by the operation of relay **T** from earth over the last contact in the arc of wiper **G** and the relevant test wiper and resistance **YC** to battery and relay **H** is operated. Contact **h8** connects earth over the low resistance upper 25 winding of relay **T**, wiper **M7** and the test wiper in its last contact position, and contact **b2** to relay **C** which thereupon re-operates. Relay **A** is connected over the last contacts in the line 30 wire arcs and resistance **YA** to a wire that is alternately connected to battery and earth, and a flashing signal is reverted to the out-going exchange. Contacts **h6** and **c5** connect the left-hand winding of relay **A** in a busy tone circuit which is earthed at one end and connected alternately to battery and earth at its other end but in the opposite phase to that connected to resistance **YA** so that relay **A** is held over its two windings alternately. The tone is induced into the line winding of relay **A** and reverted over the 35 junction. A circuit for the appropriate overflow meter is closed over contacts **b7**, **h5**, **c4** and wiper **M8**. Release takes place by the opening of the loop at the outgoing exchange, releasing relay **A** during a tone period, which is followed by the 40 release of relay **B** and, on the opening of contact **b5**, by the release of relay **H**. Relay **C** is released at contact **b2**.

If a dead number is called, the selector will not be started. To provide for this, contacts in 50 the arc of wiper **M4** relevant to unused numbers are connected to the normal contact in the arc of wiper **G** so that relay **T** will be operated immediately over a circuit extending from ground over wiper **M4**, the contact in the arc of wiper **M4**, 55 wipers **M4** and **G**, both windings of relay **T**, wiper **M7**, and the normal contact in the arc of the appropriate test wiper to which battery will be connected. Relay **H** will be operated and NU tone will be reverted from a tone circuit connected to 60 the normal contacts in the arcs of the line wire wipers.

If the selector is held for longer than a prescribed period before the digit for its setting is received the operation of a relay connected in 65 series with lamp **PG** will cause an alarm to be given.

The selector shown in Fig. 2 is connected to a junction seized in response to either of a pair of values of a digit, conveniently odd and even 70 values. The selector is operated in an exactly similar manner to that shown in Fig. 1 and the following description will be confined to the circuits and arrangements that differ from those of Fig. 1 due to the pairing of digital values.

75 The selector gives access to ten groups of 25

outlets each, each group being selectable by either of a pair of digital values, a discriminating signal being passed forward to differentiate between the two digital values denoting a group of outlets. The contact arc of wiper G of the selector is divided into two parts, 25 contacts in one part being commoned and connected to a back contact of a discriminating relay for control of search in an outlet group in respect of seizure of the junction by an even digital value, and 25 contacts in the other part being commoned and connected to a front contact of the discriminating relay for control of search in an outlet group in respect of seizure of the junction by an odd digital value. The discriminating relay is designated P and is adapted to be operated in series with the impulse receiving relay A at the time the junction is seized unless it is shunted by an earth on the positive wire at the outgoing end of the junction. The wiper and contact arc of the digit switch, designated M4 in Fig. 1 is not required for marking purposes and in Fig. 2 this wiper and wiper M8 are used for the connection of overflow meters. Outlets from the selector not in use are connected to a NU tone circuit.

When the junction is taken into use, relay A operates either over the junction loop and contact h3, wiper M2 and the right-hand winding of relay P to earth or to an earth on the positive wire at the outgoing end of the junction. If the junction is taken into use by the even value of the pair of digit values, relay P is not operated due to the shunt over the positive wire, and earth over contact p2 is connected to the first common set of 25 contacts in the arc of the wiper G. The dialled impulse train for the setting of the selector is received by relay A and repeated to the digit switch in exactly the same manner as that described for Fig. 1 and at the end of the train search takes place in the outlet group marked by the digit switch. This group will comprise the first 25 outlets connected to the arcs of the selector, the corresponding wipers of which are connected up by the digit switch in the position to which it has been set. The group is selectable by a pair of digital values, the selector wipers being connected to pairs of adjacent contacts in the arcs of the digit switch. If the received train comprises an even number of impulses earth will be connected over contact b6, wiper M2 and contact c6 to the positive wire to shunt the discriminating relay in the succeeding selector. If the received train comprises an odd number of impulses this earth will not be present and the discriminating relay in the succeeding selector will be operated in series with the impulse receiving relay over the junction loop. If a state of congestion is encountered the selector will continue in rotation until the last contact position is reached, whereupon it will be stopped by the operation of relay T in a circuit from earth on the last contact in the arc of wiper G to battery over resistance YC connected to the last contacts in the several test wire arcs, exactly as described for Fig. 1. Relays H and C will be operated and the appropriate overflow meter connected to the arc of wiper M8 will be operated from earth over contacts b7, h5, c4 and p3. Busy tone and flash signal will be transmitted in the same manner earlier described.

If the junction is taken into use by the odd value of the pair of digital values, there will be no earth present on the positive wire at the outgoing end of the junction and relay P will operate in series with relay A and will lock up over its

left-hand winding contacts p1 and b7. Contact p2 will apply the marking earth to the later set of 25 contacts commoned in the arc of wiper G, and search by the selector will take place in the outlet group marked by the digit switch. A discriminating signal will be passed forward as before described to differentiate between the pair of digital values marking the same outlet group. If congestion is encountered busy tone and flash signal will be reverted in the before-described manner and the appropriate overflow meter will be operated over the front of contact p3 and wiper M4.

In the event of a spare number being dialled, 15 the selector will be stopped on the first contacts of the group designated by that number, the contact in the relevant test wire arc being connected to battery and the corresponding contacts in the line wire arcs being connected to a source of 20 NU tone which is reverted in the manner earlier described. Although the two groups of a pair have been considered as possessing 25 outlets each, it is not necessary that this should be so. The only consideration is that the total outlets 25 in a pair of groups should not exceed 50 and that outlets in each odd or even group correspond in number.

I claim:

1. In a selecting system, a selecting switch comprising a plurality of sets of wipers and a marking wiper common to said sets, an arc of contacts associated with each of said wipers, each arc divided into a plurality of contact sections and each section in the arcs associated with said wiper sets having a plurality of outlets connected to the contacts therein and accessible over the wiper set thereof, each arc section associated with said marking wiper corresponding to an arc section associated with each wiper set, selecting means, impulse responsive means operated upon receipt of a series of impulses representing a particular digit for operating said selecting means to select a particular wiper set dependent on the number of impulses in the received series, different digits selecting different wiper sets, marking means also operated by said impulse responsive means to mark the contacts in one of said contact sections accessible to said marking wiper dependent on the number of impulses in the received series, and means effective thereafter for causing operation of said wiper sets and marking wiper to thereby cause selection of a particular outlet by the selected wiper set in the section of the contact arc corresponding to the section marked in the banks accessible to the marking wiper.

2. In a selecting system, a plurality of groups of outlets, an automatic selecting switch comprising a plurality of sets of wipers, each set having access only to certain of said groups of outlets, marking means, impulse responsive means operated by received series of impulses for operating said marking means in accordance with a received series of impulses representing a particular digit 60 to mark one of the groups of outlets accessible to each of said sets of wipers, different groups being marked by different digits, selecting means also operated by said impulse responsive means in accordance with said received series of impulses 65 representing said particular digit to select one set of wipers, different sets being selected by different digits, and means effective after said wiper set selection for moving the wipers to select one of the outlets in the marked group of outlets accessible to said selected set of wipers.

3. In a selecting system, a plurality of groups of outlets, an automatic selecting switch comprising a plurality of sets of wipers, each set having access only to certain of said groups of outlets, marking means, impulse responsive means operated by received series of impulses for operating said marking means in one instance in accordance with a received series of impulses representing a particular digit to mark one of said groups of outlets accessible to one of said wiper sets and in another instance in accordance with a different received series of impulses representing a different digit to mark a different one of said groups accessible to said one wiper set, different groups being marked by different digits, selecting means also operated by said impulse responsive means to select said one wiper set in either instance in accordance with the digit received, and means effective after said marking and selecting for moving the selected wipers to select one of the outlets in said one marked group of outlets in said one instance and for operating the wipers to select one of the outlets in said different marked group of outlets in said other instance.

4. In an automatic selector switch, a plurality of wipers comprising a plurality of sets of line wipers and a marking wiper common to said sets, a plurality of groups of lines accessible from each of said sets, a plurality of marking contacts accessible to said marking wiper, a selecting device, impulse responsive means operated by received series of impulses for operating said selecting device in accordance with a series of impulses representing a particular digit to select one of said sets of wipers, different sets being selected by different digits, a marking device also operated by said impulse responsive means in accordance with the same series of impulses to mark one of said marking contacts, different contacts being marked by different digits, means for moving said plurality of wipers in unison after said selection and marking, and means responsive to the movement of said marking wiper to said marked contact to cause said selected set of wipers to establish a connection with a line in one of said marked groups of lines.

5. In an automatic selector switch, a plurality of wipers comprising a plurality of sets of line wipers and a marking wiper common to said sets, a plurality of groups of lines accessible from each of said sets, a plurality of marking contacts accessible to said marking wiper, a selecting device, impulse responsive means operated by received series of impulses for operating said selecting device in accordance with one or another of two different series of impulses representing two particular digits to select one of said sets of wipers, different sets being selected by different pairs of digits, a marking device also operated by said impulse responsive means to mark one of said marking contacts in accordance with the same said one series of impulses in one instance and to mark another of said marking contacts in accordance with the same said other series of impulses in another instance, dif-

ferent contacts being marked by different digits, means for moving said plurality of wipers in unison after said wiper selection and contact marking, and means responsive to the movement of said marking wiper to said one marked contact to cause said selected set of wipers to establish a connection with a line in one of said groups of lines accessible from said selected set of wipers in one instance and responsive to the movement of said marking wiper to said other marked contact to cause said selected set of wipers to establish a connection with a line in another of said groups of lines accessible from said selected set of wipers in another instance.

6. In a selecting system, a first selecting device comprising a plurality of test wipers and a marking wiper common to said test wipers, a plurality of test contacts accessible to each test wiper, the test contacts accessible to each test wiper being divided into two groups, a plurality of marking contacts accessible to said marking wiper, the marking contacts being divided into two groups, each marking contact group corresponding to a different test contact group accessible to each test wiper, a second selecting device comprising a test wiper selecting wiper and a marking contact selecting wiper, impulse responsive means operated by received series of impulses for operating said second selecting device to cause said test wiper selecting wiper to select one of said test wipers in accordance with either of two different received series of impulses representing two particular digits, different test wipers being selected by either one of two digits in different pairs of digits, and to cause said marking contact selecting wiper to select and mark all of the contacts in one or the other of the two groups of marking contacts depending on the particular digit received, each of the two groups of marking contacts being selected by different digits in said pairs of digits, and means operated after said test wiper selection and contact group marking to cause said first selecting means to operate to move said test wipers and said marking wiper in unison to cause said selected test wiper to select a test contact in the group of test contacts accessible to said test wiper corresponding to the marked group of marking contacts.
